UNITED STATES PATENT OFFICE.

FREDRICH J. RODE, OF CHICAGO, ILLINOIS, ASSIGNOR TO MARQUETTE TOOL & MANUFACTURING CO., OF CHICAGO, ILLINOIS, A CORPORATION OF ILLINOIS.

DRAWING PRESS.

Application filed February 11, 1924. Serial No. 691,911.

In drawing sheet metal upon a drawing press a certain portion of the power of the press is required to form the metal into the shape of the die, but if the blank is to be held 5 so as to prevent it from buckling or wrinkling during the forming operation, then additional power is required for thus holding the blank.

The type of die cushions heretofore employed, exerts its pressure upon the blank holder ring and to overcome this pressure of the die and cushion, a portion of the power of the press must be employed.

It is one of the objects of the present invention to provide improved blank holding means which will obviate the necessity of utilizing any portion of the power of the press for actuating the blank holding means, so that the entire power of the press may be 20 employed upon the work to shape the latter.

A further object of this invention is to provide in a press of this character improved means whereby the parts of the blank holding means may be adjusted to compensate 25 the adjustments of the ram or plunger required for the various kinds of work, that is the depth of the draw of different jobs and the thickness of the material, as well as any other adjustments necessary for installation 30 purposes.

A further object is to provide an improved structure of this character including fluid control cushioning means operating upon the draw ring and improved means for retarding the return of the draw ring.

To the attainment of these ends and the accomplishment of other new and useful objects as will appear, the invention consists in the features of novelty in substantially 40 the construction, combination and arrangement of the several parts hereinafter more fully described and claimed and shown in the accompanying drawings illustrating this invention and in which—

45 Figure 1 is a view in vertical section of a portion of a draw press having a cushioning device constructed in accordance with the principles of this invention attached thereto and showing the parts in one position at the start of the drawing operation.

50 Figure 2 is a view similar to Figure 1, showing the parts of the press in the same position and with a portion of the cushion adjusted with respect to the plunger or ram.

Figure 3 is a view similar to Figure 1 of a modified form of the invention.

Figure 4 is an enlarged detail sectional view taken on line 4—4, Figure 1.

Referring more particularly to the drawings the numeral 10 designates the bolster or bed plate of a draw press, 11 a reciprocating ram or plunger, 12 a die member carried by the plunger, 13 a forming block mounted upon the bed plate 10, 14 a draw ring encompassing the forming block and co-operating with the die member 12 to clamp the material 15, 16 supporting pins for the draw ring 14, and 17 a pin plate against which the pins 16 rest to be supported thereby. All of the above referred to parts are of the ordinary and well-known construction in presses of this character.

A hanger is connected with the plunger 11 to depend therefrom and preferably embodies bars or rods 18, one end of each of which is secured as at 19 to the plunger and the other extremities of the bars or rods are provided with screw threads 20.

A supporting member 21 is connected with the bars 18 preferably through the medium of threaded collars 22 which are journaled in the member 21 and have engagement with the threads 20 on the respective rods 18. The member 21 is adapted to be adjusted upon the rods 18 toward and away from the plunger 11 by rotating the collars 22 and these collars may be rotated in any suitable manner such as by means of an endless chain 23 which passes over toothed wheels (not shown) connected with the collars 22.

Disposed between the pin supporting plate 17 and the supporting member 21 is a fluid pressure cushioning device embodying a cylinder 24 which is supported by and secured to the member 21 in any desired or suitable manner such as by means of fastening devices 25. Within the cylinder 24 is a piston 26 having connected therewith a piston rod 27, which latter is secured in any suitable manner such as by means of fastening devices 28 to the pin supporting plate 17. The piston rod 27 passes through an opening in the closed end 29 of the cylinder 24 and suitable packing 30 may be provided to form a fluid tight joint.

Discharging into the bottom of the cylinder 24 on one side of the piston 26 is a pipe

31 which is connected with any suitable source of fluid pressure supply.

The cylinder 25 is provided with an opening 32 in the wall thereof between the closed 5 end 29 and the other side of the piston 26, and connected with this opening 32 is a pipe 33, which leads to a suitable source of fluid pressure supply as at 34.

Interposed between the pipes 33 and 34 is 10 a valve casing 35, having an opening 36 to which the pipe 33 is connected and an opening 37 to which the pipe 34 is connected. The casing 35 is also provided with an opening 38 leading to the atmosphere. Within 15 the casing 35 is a rotary valve 39 having an opening 40, and which opening is of such a configuration that the valve 39 may be rotated to connect the pipe 33 with either the opening 37 or 38 in the casing 35, to direct 20 fluid pressure into the cylinder between the piston 26 and the end 29 or to permit the escape of the fluid pressure from such portion of the cylinder through the opening 38 to the atmosphere.

25 Connected with the valve 39 is a handle or lever 41 adapted to be engaged by fingers or tappets 42-43, adjustably connected with the rod 44, according to the direction of movement of the rod.

30 The rod 44 is connected with any suitable movable portion of the press so that at a predetermined time in the cycle of operation of the press the valve 39 will be automatically shifted or rotated.

35 In the operation of the device the parts will assume the position as shown in Figure 1 just at the commencement of the forming of the article. As the plunger 11 is lowered the draw ring 14 will be depressed with respect to the forming block 13 and the material 15 will be formed over the latter. During the descent of the draw ring 14 the pin plate 17 will be lowered and with it the piston 26, the cylinder 24 being held stationary 40 or in a fixed position with respect to the plunger 11. The operation of the piston in the cylinder 24 will be against the fluid pressure in the bottom of the cylinder and during this lowering movement of the piston 45 the valve 39 will be in the position shown in Figure 1 to permit outside air to be drawn into the cylinder above the piston.

50 After the article has been shaped the plunger will begin to recede or ascend and at this time in the operation of the apparatus the valve 39 may be shifted so as to connect the pipe 34 with the pipe 33 to permit fluid pressure to be admitted into the cylinder 24 on the other side of the piston 26. 55 It will be noted that by reason of the piston rod 27, the area on the upper side of the piston 26 is reduced or smaller than the area of the piston on the lower side. By reason 60 of this construction there will be a slightly greater fluid pressure against the piston on

the lower side than on the upper side and which pressure is sufficient to return the draw ring 14 to its normal or initial position. The feature, however, of reducing the areas of the piston surfaces against which 70 the fluid pressure acts, while described herein for the purpose of a clear understanding of this invention, does not constitute a portion of the subject matter of the present application but forms the subject matter of a co-pending application, Serial Number 691,653. 75

The blank holding means may be adjusted to compensate the adjustments of the ram or plunger required for various kinds of work, that is the depth of draw of different jobs 80 and the varying sizes of the different dies, and this is accomplished by adjusting the collars 24 upon the rods 18 to move the support 21 toward or away from the plunger 11 and when so adjusted will remain in a fixed 85 position with respect to the plunger.

Commercial sheets of metal from which the articles are formed upon this press, vary in thickness to such an extent that it is frequently necessary to measure and assort the 90 sheets.

By the use of the present invention the cushioning device will cause the blank holding means to automatically adjust itself to compensate the varying thickness in the material. 95

With this construction it will also be manifest that the strain of the cushioning device and blank gripping means is separate from the power of the press so that the entire 100 power of the press may be utilized in the formation of the article and no portion thereof will be employed for use in connection with the blank holding or gripping means.

In the form of the invention shown in 105 Figures 3 and 4, supplemental means are provided for assisting in sustaining the weight of certain portions of the mechanism such as the draw ring 14, pins 16, pin plate 17, piston rod 27 and piston 26.

110 This supplemental means is also preferably of a fluid pressure cushion construction, any number of which cushions may be employed. Each of these cushioning devices consists essentially of a cylinder 45 having a piston 46 therein. The piston may be adjustably connected with a tubular piston rod 47 and the piston and rod are anchored to the bed or bolster plate 10, through the medium of a bolt 48, which passes through the tubular member 47, and has secured to the free end thereof a nut or collar 49. A washer 50 may be interposed between the nut or collar and the end of the tubular member 47. The piston 46 may be threaded as at 51 upon 115 the tubular member 47 so as to permit relative adjustment thereof and discharging through the piston 46 is a pipe 52 and which pipe 52 is connected with any suitable source 120 of fluid pressure supply. 125 130

The cylinder 45 is preferably open at its bottom and the closed end 53 of the cylinder is engaged by the pin plate 17 and upon which cylinder the plate rests, the plate 17 being provided with openings 54 through which the tubular member 47 loosely passes.

Any number of these supplemental cushioning devices may be provided and the pipe 52 leading therefrom may be connected with the coupling 55 so that the fluid pressure may be led from the source of supply and be distributed to the various cylinders 45.

In use, the supplemental cushioning device is employed for sustaining the weight of the parts and after the formation of the article or at any desired point in the cycle of operation of the machine, fluid pressure may be admitted into or released from the cylinder 45 between the piston 46 and the closed end 43 of the cylinder and this fluid pressure may be of any desired degree in relation to the fluid pressure in the blank holding cushioning device.

While the preferred forms of the invention have been herein shown and described it is to be understood that various changes may be made in the details of construction and in the combination and arrangement of the several parts, within the scope of the claims, without departing from the spirit of this invention.

What is claimed as new is:

1. A drawing press including a plunger, blank holding means co-operating with the plunger to grip the work, a fluid pressure cushion for the said blank holding means, said cushion including co-operating parts movable relatively one with respect to the other, means connecting one of the cushion parts with the blank holder, means securing the other part of the cushion to the said plunger for movement therewith and in a fixed position with respect thereto, and means for varying at will the fixed position of the plunger and the cushion part which is secured thereto.

2. A drawing press including a plunger, a blank holder co-operating with the plunger for clamping the work, hangers depending from the plunger, a support, means connecting the support with the hangers for movement with the plunger in a fixed position with relation thereto and for adjustment with respect to the plunger, and a fluid pressure cushion including a piston and cylinder relatively movable one with respect to the other, the cylinder and piston being connected one with the said support and the other with the said blank holding means.

3. A drawing press including a plunger, a blank holder co-operating with the plunger for clamping the work, hangers depending from the plunger, a support, means connecting the support with the hangers for move-

ment with the plunger in a fixed position with relation thereto and for adjustment with respect to the plunger, a fluid pressure cushion including a piston and cylinder relatively movable one with respect to the other, 70 the cylinder and piston being connected one with the said support and the other with the said blank holding means, and means for supplying fluid pressure to the cushion.

4. A drawing press including a plunger, 75 a blank holder co-operating with the plunger for clamping the work, hangers depending from the plunger, a support, means connecting the support with the hangers for movement with the plunger in a fixed position with relation thereto and for adjustment with respect to the plunger, a fluid pressure cushion including a piston and cylinder relatively movable one with respect to the other, 80 the cylinder and piston being connected one with the said support and the other with the said blank holding means, means for supplying fluid pressure to one side of the cushion, and means for supplying fluid pressure to the other side 85 of the said cushion.

5. A drawing press including a plunger, a blank holder co-operating with the plunger for clamping the work, hangers depending from the plunger, a support, means connecting the support with the hangers for movement with the plunger in a fixed position with relation thereto and for adjustment with respect to the plunger, a fluid pressure cushion including a piston and cylinder relatively movable one with respect to the other, 90 the cylinder and piston being connected one with the said support and the other with the said blank holding means, means for supplying fluid pressure to one side of the cushion, and means operating automatically to supply pressure to the other side of the cushion.

6. A drawing press including a plunger, 95 a blank holder co-operating with the plunger for clamping the work, hangers depending from the plunger, a support, means connecting the support with the hangers for movement with the plunger in a fixed position with relation thereto and for adjustment with respect to the plunger, a fluid pressure cushion including a piston and cylinder relatively movable one with respect to the other, 100 the cylinder and piston being connected one with the said support and the other with the said blank holding means, means for supplying fluid pressure to one side of the cushion, and means including valve mechanism for directing pressure to the other side of the cushion to operate in 105 opposition to the fluid pressure on the first recited side of the cushion.

7. A drawing press including a plunger, 110 a blank holder co-operating with the plunger for clamping the work, hangers depending 115

from the plunger; a support, means connecting the support with the hangers for movement with the plunger in a fixed position with relation thereto and for adjustment with respect to the plunger, a fluid pressure cushion including a piston and cylinder relatively movable one with respect to the other, the cylinder and piston being connected one with the said support and the other with the said blank holding means, and additional means for sustaining the weight of certain of the said parts.

8. A drawing press including a plunger, a blank holder co-operating with the plunger for clamping the work, hangers depending from the plunger, a support, means connecting the support with the hangers for movement with the plunger in a fixed position with relation thereto and for adjustment with respect to the plunger, a fluid pressure cushion including a piston and cylinder relatively movable one with respect to the other, the cylinder and piston being connected one with the said support and the other with the said blank holding means, and additional fluid pressure means for sustaining the weight of certain of the said parts.

9. A drawing press including a plunger, a blank holder co-operating with the plunger for clamping the work, a fluid pressure cushion for the blank holder, said cushion including relatively movable parts, and

means adjustably securing one of the parts of the cushion to the plunger for movement therewith and in a fixed position with relation thereto, the said blank holding means operating to compensate the varying thicknesses in the material being operated upon and while a uniform pressure is being maintained upon the said blank holding means.

10. In a power press, the combination with a sheet metal forming die, fluid pressure means for holding the blank, said means including a piston and cylinder members, one of the said members being adjustably connected with a movable part of the press, and means whereby the position of the piston within the cylinder, one with relation to the other, will remain constant during the forming of the material.

11. In a power press, the combination with a sheet metal forming die, fluid pressure means for holding the blank, said means including a piston and cylinder members, one of the said members being adjustably connected with a movable part of the press, and means whereby the pressure upon the material will remain constant during the forming operation.

In testimony whereof I have signed my name to this specification on this 5th day of February, A. D. 1924.

FREDRICH J. RODE.
